UNITED STATES PATENT OFFICE.

GEORGE C. ANDREWS, OF MINNEAPOLIS, MINNESOTA.

THERMOSTAT.

1,131,651.

Specification of Letters Patent. Patented Mar. 16, 1915.

Application filed March 20, 1913. Serial No. 685,118.

To all whom it may concern:

Be it known that I, GEORGE C. ANDREWS, a citizen of the United States, residing at Minneapolis, in the county of Hennepin and State of Minnesota, have invented certain new and useful Improvements in Thermos- 5 stats; and I do hereby declare the following to be a full, clear, and exact description of the invention such as will enable others skilled in the art to which it appertains to 10 make and use the same.

My invention has for its particular object to simplify the construction and improve the action of temperature regulators 15 of that type wherein an electric circuit having contacts controlled by a thermally expanded or extended controlling element, is utilized to control the actions of a suitable motor, which, in turn, controls dampers, 20 valves, or similar elements of a furnace or other heat producing medium.

Generally stated, the invention consists of the novel devices and combinations of devices hereinafter described and defined in 25 the claims.

In the accompanying drawings which illustrate the invention, like characters indicate like parts throughout the several views.

Referring to the drawings, Figure 1 is a 30 view in front elevation showing the improved temperature regulator with a thermometer attached; Fig. 2 is a view corresponding to Fig. 1 with the thermometer removed; Fig. 3 is a rear elevation of the regulator; Fig. 4 is a horizontal section taken approximately on the line $x^4 x^4$ on Fig. 3; Fig. 5 is a detail view in plan showing a knob or finger piece and coöperating crank for adjustably setting the contacts of the 40 regulator; Fig. 6 is a fragmentary view in end elevation showing the upper end portion of a thermally operated contact arm; and Fig. 7 is a fragmentary view in front elevation illustrating a slight modification of the 45 fulcrum which supports the thermally operated contact arm.

The various parts of the regulator proper are mounted directly or indirectly upon a base or back member 1, preferably pressed 50 or bent into channel shape form from thin sheet metal. One side of the base 1 is provided with a vertically extended and outwardly projecting flange or bar 2 to which is anchored the ends of a flexible steel ribbon 55 3. This ribbon 3 is slightly bowed and the bow thereof will be increased by relatively high and decreased by relatively low tem-

peratures. The said element 3 constitutes the primary thermally operated controlling element of the regulator, but constitutes, 60 *per se*, no part of the present invention, being an element well known for that purpose, and it should be understood that so far as the broad idea of my invention is concerned, this primary controlling element may take 65 different forms.

Of the three contacts which control the flow of the current through the three-line circuit, in the usual way, the numerals 4-4 indicate the opposing relatively fixed contacts, and the numeral 5 indicates the relatively movable contact which works between and alternately engages the said contacts. The so-called relatively fixed contacts 4 are, as is usual, in the form of screws that work 75 adjustably through binding posts 6-6, insulated from but secured to an adjustable contact carrier in the form of a segment 7, pivotally connected at 8 to the back surface 80 of the face of the base 1. The binding posts 6 which are insulated from each other, project through a segmental slot 9 cut in the face of the base 1. The so-called relatively 85 movable intermediate contact 5 is shown as secured to the lower end of a lever 10, which, at its upper end is provided with knifed edge or V-shaped fulcrum lugs 11 projecting from both sides thereof, and seated for oscillatory movements in V-shaped notches 12 formed in a fulcrumed bracket 13 and in 90 the base flange 2^a of the bar 2. The said parts 1, 2 and 13 are all rigidly secured together, and the said element 13 is spaced 95 from the said flange 2^a. The extreme upper end of the lever 10, above its fulcrum lugs 11, is shown as notched to form prongs, one of which is connected to the central portion of the ribbon 3 by means of a light connecting rod or link 14. A very light coiled spring 15 is, as shown, connected at 100 one end to the flange 2^a, and at its other end to the lever 10 at a point below its fulcrum lugs 11. The spring 15 keeps the knife edges of the fulcrum lugs 11 lightly seated in the notches 12 and the said lugs afford a 105 fulcrum for the said lever which operates practically without friction. This makes the instrument very sensitive in its action and is, therefore, a highly important feature in a device of this kind where great accuracy and delicacy of action is required.

In the preferred arrangement best shown in Fig. 2, the fulcrum lugs 11 have their bearing edges projecting at one side, but in

the modified construction illustrated in Fig. 7, the corresponding fulcrum lugs 11^a have their bearing edges turned downward, and the fulcrum seats 12^a are correspondingly positioned. Also, the fulcrum bracket 13^a employed in the said modified construction is of slightly different form from that shown in Fig. 2, and the spring 15^a, as well as the light connecting rod 14^a are extended approximately horizontal, but deviate from horizontal alinement slightly, so as to exert a slight downward pressure on the fulcrum lugs which assist gravity in holding the said lugs properly seated.

15 As is well understood, the temperature at which the regulator will operate either to open or close the dampers of a furnace, or will perform some similar function, will depend on the position in which the relatively fixed contacts 4 are set, in a direction from right to left in respect to Figs. 1, 2 and 3. Hitherto, the adjustments of the contacts carrier 7 have been accomplished by the oscillation of the controlling knob or finger piece having a pointer coöperating with the temperature scale to indicate the temperature which the controller will operate. It has been customary however to provide the stem of such a knob with a pinion meshing with the segmental gear of the said segment 7, or corresponding part. My invention provides an improvement in this connecting device, whereby much less lost motion, and hence, better accuracy in the setting is obtained. The setting knob 16 is shown as provided with the usual pointer 17 that coöperates with the temperature scale 18 marked on the lower portion of the face of the base 1. The numeral 19 indicates a crank in the form of a disk provided with a stem 20 pivoted in and extended through the lower portion of the base 1 and driven into a seat in the knob 16 with sufficient friction to secure the said parts 16 and 19 for common oscillatory movements. A link 21 connects one lower side portion of the vibratory contact carrier 7 with an eccentric portion of the crank disk 19, so that by oscillatory movements of the knob 16, the desired adjustments of the contact carrier 7 are accomplished. Preferably, and as shown, the link 21 is formed by a short section of a light rod or heavy wire having its ends bent and passed through perforations in the said elements 7 and 19 and upset or riveted so as to hold the said link in working position.

60 The numeral 22 indicates a thermometer shown as secured to a light pressed sheet metal outer casing 23 which, in turn, is detachably secured to the base 1 and covers the lever 10 and certain other parts but leaves the knob 16, scale 18 and contacts

4—5 exposed. The base 1, at its upper end portion is shown as provided with a backwardly pressed flange 24 having perforations, through which, nails or screws may be passed to secure the regulator to a wall or any other suitable place.

What I claim is:

1. In a temperature regulator, a contact lever having knife edge contact lugs projecting from its opposite sides, seats for the said lugs formed on a relatively fixed part of said regulator, a thermally actuated controller for said lever having a link connected thereto on one side of its fulcrum lugs, and a spring connected to said lever on the opposite side of said fulcrum lugs, the said link and spring extending from said lever in the same direction and exerting a force on said lever holding the fulcrum lugs thereof seated irrespective of gravity.

2. In a temperature regulator, the combination with relatively fixed contacts and a coöperating intermediate relatively movable contact, of an upright lever carrying said movable contact and provided with knife edge fulcrum lugs seated in a relatively fixed part of said regulator, a thermally actuated expandible controlling element, a link connecting the latter to said lever close to but on one side of its fulcrum lugs, and a light coiled spring anchored at one end and connected at its other end to said lever on the other side of its fulcrum lugs.

3. In a temperature regulator, the combination with relatively fixed contacts and a coöperating intermediate thermally controlled contact, of a vibratory contact carrier adjustably supporting said relatively fixed contacts, an operating knob, and a link connecting an eccentric portion of said knob to said vibratory contact carrier for adjusting said relatively fixed contacts in respect to the intermediate contact.

4. In a temperature regulator, the combination with a base member, of relatively fixed contacts, a coöperating intermediate thermally actuated contact, an oscillatory contact carrier adjustably supporting said relatively fixed contacts, an operating knob, a crank disk having a stem passed through and rotatably seated in said base and frictionally driven into said knob, and a link having laterally bent ends pivotally connected to said contact carrier and to said crank disk.

In testimony whereof I affix my signature in presence of two witnesses.

GEORGE C. ANDREWS.
